[57] **CLAIM**

The ornamental design for an ash tray, as shown and described.

DESCRIPTION

FIG. 1 is a right front perspective view of an ash tray showing my new design;

FIG. 2 is a left side elevational view thereof, the right side being a mirror-image of the left side;

FIG. 3 is a rear elevational view thereof, the front being a mirror-image of the rear;

FIG. 4 is a top plan view thereof; and,

FIG. 5 is a bottom plan view on a smaller scale thereof.
